Application November 16, 1940, Serial No. 366,003

18 Claims. (Cl. 115—17)

The invention relates generally to outboard marine motors and more particularly to the underwater portions thereof.

The general object of the invention is to provide a novel arrangement in a water-cooled outboard motor of an underwater shaft housing, the pump for supplying water to the engine, the anti-cavitation plate, and the exhaust pipe.

It is also an object to provide a pump to supply water to the engine, located below the water line but above the underwater shaft housing and housed in the vertical drive shaft casing with the drive shaft carrying the operating part of the pump.

Another object is to provide a water pump for an outboard motor, located within the drive shaft casing of the motor and utilizing a portion of the interior of said casing as a part of the water inlet passage.

A further object is to provide a water pump for an outboard motor, located within the drive shaft casing of the motor, and an anti-cavitation plate surrounding that portion of said casing in which the pump is located, with the plate provided with portions serving as part of or functioning with the water passages of the pump.

Still another object is to provide in an outboard motor a water pump, an exhaust pipe, and an anticavitation plate supporting in a novel manner portions of both the pump and exhaust pipe.

A still further object is to provide in an outboard motor an anticavitation plate and an exhaust pipe, the lower end of which bears a novel relation to and is supported in a novel manner by the anticavitation plate.

Other objects and advantages will become apparent from the following description taken in connection with the accompanying drawings, in which:

Figure 1 is a side elevational view on a reduced scale of the underwater portions of an outboard motor embodying the features of the invention.

Fig. 2 is a fragmentary front elevational view.

Fig. 3 is a longitudinal vertical sectional view.

Fig. 4 is a horizontal sectional view taken on the line 4—4 of Fig. 3.

Fig. 5 is a horizontal sectional view taken on the line 5—5 of Fig. 3.

Fig. 6 is a perspective view of disassembled parts of the pump.

Fig. 7 is a fragmentary perspective view showing the means for retaining the pump in the casing.

While the invention is susceptible of various

modifications and alternative constructions, I have shown in the drawings and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims.

10 An outboard motor of the type herein contemplated comprises generally a bracket for securing the motor to the stern of a boat and supporting the motor for pivotal movement about a horizontal axis extending transverse to the length of the boat, and also for pivotal movement about a vertical axis for steering purposes. The bracket supports the engine and the latter has a downwardly extending drive shaft enclosed in a drive shaft casing. At the lower end of the drive shaft casing is a housing carrying a horizontally extending propeller shaft having a gearing connection with the drive shaft, a propeller being mounted on the drive shaft outside of the casing. The engine also has a downwardly extending exhaust pipe so that the exhaust gases may be discharged under the water. In the case of a water-cooled motor, connections are also provided for carrying water from a point below the water line upwardly to the engine.

15 The present invention involves a novel arrangement of a water pump for supplying cooling water to the engine. In the present instance the water pump is mounted on and driven by the vertically extending drive shaft. The present invention also contemplates a novel arrangement for discharging the exhaust gases below the water line.

20 As shown in the drawings which illustrate the underwater portions of the motor, the vertically extending drive shaft connected with the engine is indicated at 10. Surrounding the drive shaft 10 is a casing 11 which in the present instance is a cylindrical tube. Secured to the lower end of the drive shaft casing 11 is an underwater housing 12 into which the drive shaft 10 extends and in which is journaled a horizontal propeller shaft (not shown) having a gearing connection with the drive shaft 10. The propeller shaft extends rearwardly from the housing 12 and on its projecting end carries a propeller 13. An exhaust pipe 14 also extends downwardly from the engine to conduct the exhaust gases to a point below the water line.

25 While any suitable form of connection may be provided between the drive shaft casing 11 and

the underwater unit 12, in the present instance the upper end portion, indicated at 15, of the housing 12 is of reduced diameter and is telescoped within the lower end of the drive shaft casing 11 (see Fig. 3). To secure the housing 12 and casing 11 against relative endwise movement, a plurality of screws 16 may be threaded into the reduced portion 15 of the housing. A bushing 17 may, if desired, be placed in the housing 12 to serve as a bearing for the drive shaft 10.

In the case of outboard motors which have sufficient speed to cause cavitation adjacent the propeller, an anticavitation plate is placed above the propeller to prevent air from being drawn down from the surface of the water by such cavitation. In the present instance an anticavitation plate, indicated generally at 20, is utilized. In the preferred form, the anticavitation plate 20 comprises a rear section 21 and a front section 22. These two sections meet in a transverse plane including the axis of the drive shaft, and each has an upwardly extending hub portion 23. To clamp the two sections together and to hold them rigid with the drive shaft casing 11, the two sections are provided with enlargements 24 spaced laterally from the drive shaft casing and drilled and tapped to receive screws 25. The hub portions 23 of the two sections of the anticavitation plate are also provided with bosses 26 which are drilled and tapped to receive screws 27. Thus the two sections of the anticavitation plate are rigidly secured together and are rigidly clamped around the drive shaft casing 11.

In most outboard motors it is customary practice to have the gearing connection between the drive shaft 10 and the propeller shaft of the reducing type. Thus the drive shaft 10 has a somewhat greater speed than the propeller shaft. In the present instance, advantage is taken of this greater speed of the drive shaft 10 by having the pump driven thereby in order that the supply of cooling water to the engine may be fully adequate. The pump in the present instance is preferably of the sliding vane type and the sliding vane is carried by the drive shaft 10.

In its preferred form, the pump comprises a pump body 30 (see Figs. 3, 4 and 6) of generally cylindrical form surrounding the drive shaft 10 and snugly fitting within the interior of the drive shaft casing 11. The pump body 30 is provided with an eccentric chamber 31 in which a sliding vane 32 operates. In order to provide suitable diameters, the drive shaft casing 10 is provided with a sleeve 33 which is rigidly secured to the drive shaft and extends into the chamber 31. A transverse slot is cut through the sleeve 33 and the drive shaft 10 to slidably receive the vane 32. The lower end of the chamber 31 is open and a cover plate 34 is secured thereto as by screws extending vertically into the pump body.

The pump is preferably located immediately above the housing 12 so that the cover plate 34 rests on the top surface of the reduced portion 15 of the housing. A recess may be cut in the reduced portion 15 to receive a sealing washer 35 of cork or other suitable material. In order to facilitate assembly of the pump body 30 within the drive shaft casing 11 in their proper relative position, the outer surface of the pump body is provided with a vertically extending groove 36 (see Figs. 4 and 6) which is flared at its upper end as at 37. A lug 38 is punched inwardly in the casing 11 (see Fig. 7) to fit in the slot 36, thereby holding the casing and pump body against relative rotation. Thus, when assem-

bling the parts, the pump body 30 is slid longitudinally into the drive shaft casing and the lug 38 enters the flared portion 37 and thence is guided into the groove 36, the flared portion 37 causing the pump body to shift rotatably as much as is necessary for proper positioning.

The water intake and outlet passages for the pump are also arranged in a novel manner. Thus the pump body is provided with a radial aperture 40 opening into the chamber 31 and communicating with a vertically extending groove 41 cut in the periphery of the pump body, as shown in Figs. 4 and 6. Since the pump body 30 fits snugly within the drive shaft casing 11, the groove 41 with the drive shaft casing forms a closed passage which opens at its upper end into the interior of the drive shaft casing above the pump body. Water is supplied to the interior of the drive shaft casing so that it may be drawn into the chamber 31 through the groove 41 and the aperture 40. To this end the drive shaft casing 11 immediately above the hub 23 of the anticavitation plate on its front face is provided with a plurality of small apertures 42 through which water enters the drive shaft casing. Since these apertures face forwardly, the movement of the structure through the water forces the water in through these apertures. While the use of a plurality of small apertures, such as the apertures 42, instead of one large opening, serves to a great extent to prevent entrance of foreign material, a weed guard may be provided in front of the apertures to prevent weeds from clogging them. To this end a wire 43 may be bent in the form of a triple U, two facing downwardly and the center one facing upwardly, as shown in Fig. 2, to extend upwardly in front of the drive shaft casing. To hold the weed guard 43 in place, the ends of the wire are forced into holes drilled in the upper edge of the hub 23 of the anticavitation plate.

The outlet from the pump comprises a rearwardly extending radial aperture 44 in the pump body registering with a hole in the drive shaft casing 11 and with a passage 45 formed in an enlargement 46 of the hub portion of the rear section of the anticavitation plate. In order to hold the aperture 44, the hole in the drive shaft casing and the passage 45 in alignment, the three are counterbored to receive a cylindrical bushing 47 fitting snugly therein. The bushing 47 not only holds these openings in alignment, but further acts as a seal to prevent leakage at this point. The passage 45 in the enlargement 46 is of L shape having one leg extending upwardly to receive a pipe fitting 50 to which is connected a water pipe 51 extending upwardly to the water jacket of the engine. Preferably the pipe 51 is located immediately in the rear of the drive shaft casing 11.

The invention also includes a novel arrangement for the lower end of the exhaust pipe 14 and the relation thereof to the anticavitation plate. Such arrangement includes an exhaust pipe fitting 52 telescoped over the lower end of the exhaust pipe 14, as illustrated in Fig. 3. In the preferred construction, the exhaust pipe 14 and the fitting 52 are of streamlined construction of the type having a bluntly rounded front contour and a trailing rear contour. To rigidly hold the fitting 52 in place, the anticavitation plate 21 has secured to its upper surface a ring 53. In the preferred construction, the ring 53 is provided with a transverse rib 54 and a lug 55 into which screws 56 are threaded from the anti-

cavitation plate 21. The ring 53 is shaped to telescope into the lower end of the exhaust pipe 14 and the fitting 52 and thus hold them in place. To secure the two rigidly together, a screw 51 may extend through the fitting 52 and be threaded into the side of the ring 53. The fitting 52 is provided with a rearwardly and downwardly extending nozzle portion 58 which communicates with a rearward opening 59 in the exhaust pipe 14 and which carries the exhaust gases to a point spaced rearwardly from the propeller so that they are carried away by the stream of water forced rearwardly by the propeller.

The arrangement of the various parts herein shown is such that they all may be very readily assembled, or disassembled in case of repair. Thus the pump may be put in place around the drive shaft and within the drive shaft casing 11, and the lower housing 12 assembled within the casing. The two parts of the anticavitation plate are then readily assembled with the bushing 47 holding the various openings comprising the outlet of the pump in alignment. At the same time that the rear section of the anticavitation plate is put in place, the exhaust fitting 52 and its supporting ring 53 may be secured in place. These parts it will be noted may be readily disassembled in case of repair.

From the foregoing, it will be apparent that I have provided a novel arrangement for a pump to supply cooling water to the engine. While it is located below the water line it is housed within the vertical drive shaft casing so that it may be driven by the higher speed drive shaft rather than the propeller shaft. The drive shaft itself carries the operating part of the pump, namely, the vane, and the drive shaft casing above the pump serves as part of the pump intake. The anticavitation plate has a portion provided with a passage constituting a part of the outlet for a pump and providing a convenient means for securing the lower end of the pipe which conducts the water up to the engine jacket. The anticavitation plate also serves to steady and hold in place the lower end of the exhaust pipe.

I claim as my invention:

1. In an outboard motor the combination of a vertically positioned cylindrical tube of substantially uniform diameter, a shaft housing having its upper end telescoped within said tube, a drive shaft mounted within said tube and extending into said housing, a pump body mounted within and held against rotation by said tube and resting on the upper end of said housing, and a rotatably operating pump element located within said pump body and driven by said shaft.

2. In an outboard motor, the combination of a vertical drive shaft casing, a drive shaft extending therethrough, a pump mounted in the lower part of said casing and operated by said shaft, said pump having an intake passage in communication with the interior of the drive shaft casing above the pump, and means permitting a flow of water into the interior of said casing located above said pump.

3. In an outboard motor, the combination of a vertical drive shaft casing, a drive shaft extending therethrough, a rotary pump located within the lower portion of said casing and operated by said drive shaft, and an anticavitation plate mounted on said casing and having a hub surrounding that portion of the casing within which said pump is located.

4. In an outboard motor, the combination of a vertical drive shaft casing, a drive shaft within

said casing, a pump located within said casing and operated by said shaft, a water intake for said pump in said casing above the pump, an anticavitation plate mounted on said casing and having a hub surrounding that portion of the casing within which the pump is mounted, and a weed guard mounted in said hub and extending upwardly in front of said intake.

5. In an outboard motor, the combination of a vertical drive shaft casing, a drive shaft within said casing, a pump located within said casing and operated by said shaft, an anticavitation plate mounted on said casing and having a hub surrounding that portion of the casing within which the pump is mounted, said pump having an intake passage in communication with the interior of the casing above the pump, and an intake in the front of said drive shaft casing opening into the interior thereof and located above said pump and said hub.

6. In an outboard motor, the combination of a vertical drive shaft casing, a drive shaft within said casing, a pump located within said casing and operated by said shaft, said pump having an outlet passage extending through said casing, and an anticavitation plate mounted on said casing and having a hub provided with a water passage in communication with said outlet passage.

7. In an outboard motor, the combination of a vertical drive shaft casing, a drive shaft within said casing, a pump within said casing operated by said drive shaft, said pump having a rearwardly extending outlet passage extending through said casing, an anticavitation plate mounted on said casing and having a hub provided with an L-shaped water passage, one end of the passage being in communication with the outlet of the pump, and a water pipe secured to the other end of the L-shaped passage for conducting water to the engine.

8. In an outboard motor, the combination of a vertical drive shaft casing, a drive shaft within said casing, a pump within said casing operated by said shaft, said pump being provided with an outlet passage, an anticavitation plate mounted on said casing and having an enlarged portion located adjacent said outlet, said enlarged portion being provided with a water passage and said casing being provided with an aperture, and a sleeve extending through said aperture with one end located within said outlet and the other end located within the water passage in the enlarged portion of the anticavitation plate and serving to hold said outlet, said aperture and said water passage in alignment.

9. In an outboard motor, the combination of a vertical drive shaft casing, a drive shaft within said casing, a pump within said casing operated by said drive shaft and having an outlet passage, said casing having an aperture aligned with said outlet passage, an anticavitation plate mounted on said casing and comprising front and rear sections, an enlarged portion on the upper face of said plate having a water passage aligned with said aperture and said outlet, and means to clamp said front and rear sections together tightly around said casing and holding said enlarged portion in substantially water-tight relation to said casing.

10. In an outboard motor, the combination of a vertical drive shaft casing, a drive shaft within said casing, a pump within said casing operated by said drive shaft, an anticavitation plate mounted on said casing and having a water passage serving as a part of the outlet for said pump,

an exhaust pipe extending parallel to said casing, and means on the upper face of said plate for locating and supporting the lower end of the exhaust pipe.

11. In an outboard motor, the combination of a vertical drive shaft casing, a drive shaft within said casing, a pump within said casing, an anticavitation plate secured to said casing and extending rearwardly therefrom, a vertical exhaust pipe spaced rearwardly from said casing and having its lower end located and supported by said anticavitation plate, an enlarged portion on the upper face of said plate located between said exhaust pipe and said casing and having a passage therein serving as part of the outlet for the pump, and a water pipe connected to said passage and extending vertically between said casing and said exhaust pipe.

12. In an outboard motor, the combination of a vertical drive shaft casing, an anticavitation plate secured to said casing and extending rearwardly therefrom, an exhaust pipe extending downwardly at the rear of said casing, and a fitting secured to the exhaust pipe and having its lower end supported and positioned by said anticavitation plate.

13. In an outboard motor, the combination of a vertically extending drive shaft casing, an anticavitation plate mounted on said casing and extending rearwardly therefrom, a vertically extending exhaust pipe located in the rear of said casing, a fitting secured to said exhaust pipe, and a flange member secured to the upper face of said anticavitation plate and interfiting with the lower end of said fitting.

14. In an outboard motor, the combination of a vertical drive shaft casing, an anticavitation plate mounted on said casing and extending rearwardly therefrom, a vertical exhaust pipe located rearwardly of said casing, a fitting telescoped over the lower end of the exhaust pipe, and a flange member secured to the upper face of said anticavitation plate and telescoped within the lower end of said fitting.

15. In an outboard motor, the combination of 45

a vertical drive shaft casing, an anticavitation plate secured to said casing, a vertically extending exhaust pipe located rearwardly of said casing, a fitting secured to the lower end of said exhaust pipe, and means on the upper face of said anticavitation plate for supporting said fitting, said fitting being provided with a nozzle portion extending downwardly and rearwardly and located rearwardly of the rear edge of the anticavitation plate.

16. In an outboard motor, the combination of a vertical drive shaft casing, a housing secured to the lower end of said casing, a propeller carried by said housing, an anticavitation plate 15 mounted on said drive shaft casing and extending over and rearwardly beyond the propeller, an exhaust pipe located rearwardly of the drive shaft casing, and a fitting for the lower end of said exhaust pipe supported by said anticavitation plate, said fitting having a nozzle portion extending rearwardly of the rear edge of the anticavitation plate and thence downwardly at an angle at the rear of the propeller.

17. In an outboard motor, the combination of 25 a tubular drive shaft casing, a drive shaft extending through said casing, and a pump body fitting snugly within said casing adjacent one end thereof and around said shaft, said pump body being provided with a groove and said casing having an inwardly extending lug fitting in said groove to facilitate assembly of the pump body within the casing.

18. In an outboard motor, the combination of 35 a tubular drive shaft casing, a drive shaft within said casing, a pump body fitting snugly within said casing adjacent one end thereof and around said shaft, a housing unit secured within said one end of the casing, said pump body having an outlet extending through said casing, said casing and said pump body having cooperating means to angularly align the pump body within the casing, and means clamped to the outside of the casing providing a water passage connecting with said outlet.

WILLIAM L. KISSEL.
